(57) **CLAIM**

The ornamental design for an exercise equipment as shown and described.

DESCRIPTION

FIG. 1 is a front view of an exercise equipment showing my new design;

FIG. 2 is a right side view of the design shown in FIG. 1 in an alternative state;

FIG. 3 is a left side view of the design shown in FIG. 1;

FIG. 4 is a rear view of the design shown in FIG. 1;

FIG. 5 is a right side view of the design shown in FIG. 1;

FIG. 6 is a top view of the design shown in FIG. 1;

FIG. 7 is a front, right side perspective view of the design shown in FIG. 1; and,

FIG. 8 is a rear, right side perspective view of the design shown in FIG. 1.

The evenly-spaced broken lines in the Figures illustrate portions of the exercise equipment that form no part of the claimed design.

1 Claim, 8 Drawing Sheets
